UNITED STATES PATENT OFFICE.

MILTON HENRY NEWSPICKLE, OF YORK, PENNSYLVANIA.

RIM REMOVER.

Application filed March 17, 1923. Serial No. 625,821.

To all whom it may concern:

Be it known that I, MILTON H. NEWSPICKLE, a citizen of the United States, and resident of York, in the county of York and 5 State of Pennsylvania, have invented certain new and useful Improvements in Rim Removers, of which the following is a specification.

This invention relates to a device for 10 splitting a demountable rim, or breaking the joint therein when it is desirable to place a casing thereon.

Another object of my invention is the provision of the above means which may be 15 readily adjustable to various conditions without the taking apart of the device, and which may be adjusted while the device is in action.

Still another object is the provision of a 20 device of the character described which is readily adaptable to various types of rims, thus producing an efficient device which may be used interchangeably.

To this end my invention includes a pair 25 of grips adapted to be secured to a split rim on each side of the joint having supports thereon, one support adapted to serve as the fulcrum of a lever having a slide member thereon adjustably engaging the lever 30 and adapted to engage the other grip element. Manipulation of the lever handle through the various adjustments of the slide element enables the operator to move the grips either toward or away from each other 35 as it is desired to overlap or separate the ends of the rim.

I have illustrated in the drawings the preferred embodiment of my invention, in which:—

40 Fig. 1 is a side elevation of an automobile rim with my device in its initial position.

Fig. 2 is a plan view of the device of Fig. 1.

45 Fig. 3 is a side elevation of the separated rim.

Fig. 4 is a side elevation of the device in the process of separating the ends of the rim, and

50 Fig. 5 is an end elevation of the grip 2.

I have designated in the drawings, a split automobile rim as at 1 to which are secured grips 2 and 3 as by means of wing bolt 4 having a spiral spring 5 surrounding the 55 shank thereof, which causes the side plates making up the grip to readily separate up-

on backing off the wing nut when it is desired to remove the grip from the rim. One side plate in each grip is provided with support elements 6 made fast to one plate and 60 penetrating the other. Thus each grip is readily adjustable to any width of rim, as the elements 6 are of sufficient length to cover the gap between plates when used with the largest or smallest rims. 65

I also provide a lever handle 7 having a recess 8 at or near one end thereof, adapted to be supported on one of the elements 6, which serves as a fulcrum for the part 7. A toothed upper surface 9 on the handle member 7 is adapted to hold the slide 10 in any desired position. As is clearly shown in the drawings, the slide embraces the handle member, said slide having at its top depending portions 11 which serve as teeth engaging the toothed surface 9. An extension on the bottom of the slide 10 is provided with a bolt 12 to which may be secured a short length of chain, or the like, 13, carrying a swivel hook 14. 75

The operation of the device is as follows: The grips 2 and 3 are positioned on each side of the split in the rim, this position being accurately determined by practice, and the wing bolt 4 screwed up until the proper tension has been secured. The recess 8 in the handle 7 may now be placed on either of the upper supporting elements 6 in the larger grip, which elements, it will be seen, are in a higher plane than those in the other grip. The slide 10 is now placed in a position somewhere between the two grips and the hook 14 placed over one of the elements 6 in the other grip. Upward movement of the handle will cause one end of the rim to be moved upwardly and in a direction to overlap the other end of the rim. After this limit of movement has been reached the 85 recess 8 may be moved to the other supporting element 6 on the larger grip, the slide readjusted as necessary, and the upward movement of the handle continued. This operation is repeated as desired. On one of the lower supporting elements 6 in the larger grip, I provide a catch 15 which is adapted to fall over one of the supporting elements 6 in the smaller grip when that member comes in proximity to the larger grip. Thus the rim may be held in its separated position, 90 the ends overlapping, while the desired work with the casing is being completed. 100

105

110

What is claimed is:—

A device of the character described, including grips adapted to be secured to each end of a split rim, a supporting element up-
5 on one grip, a plurality of supporting ele-
ments on another grip, said elements being
arranged in a plane radial to the axis of the
rim, a lever handle having a hook shaped
end engaging one of said supporting ele-
10 ments and readily detachable therefrom,

said lever handle having a serrated upper
edge, a slide on said lever handle adjustably
engaging said serrated handle edge, a flexi-
ble member secured to the slide member and
having a hook engaging one of said grips,
movement of the handle about its pivot caus-
ing relative movement of the grips.

In testimony whereof, I affix my signature.

MILTON HENRY NEWSPICKLE.
